UNITED STATES PATENT OFFICE.

HENRIETTA PYLE, OF SAN ANTONIO, TEXAS.

HOT-WATER BOTTLE.

Application filed January 6, 1926. Serial No. 79,565.

This invention relates to hot water bottles, and aims to provide novel means whereby a hot water bottle may be secured in a pre-determined position, novel means being provided for holding the hot water bottle against movement or displacement.

A still further object of the invention is to provide a novel form of securing strap, the same being provided with a friction strip 10 to prevent movement of the water bottle with respect to the securing strap.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made 20 within the scope of what is claimed, without departing from the spirit of the invention.

Referring to the drawing:

Figure 1 is a plan view of a hot water bottle and securing device constructed in accordance with the invention.

Figure 2 is a longitudinal sectional view through one of the lateral securing wings of the bottle.

Figure 3 is a sectional view through a modified form of wing.

Figure 4 is a fragmental elevational view illustrating apertured ears for the reception of the securing straps.

Referring to the drawing in detail, the water bottle is indicated generally by the reference character 5, and as far as the body of the bottle is concerned, the same is constructed of rubber in the usual and well known manner.

Formed integral with the body of the bottle are lateral elongated wings 6 which are provided with eyelets through which the straps 7 are passed, the straps 7 being provided with enlargements 8 adapted to en-

gage the wings 6 at points adjacent to the eyelets and prevent the straps from slipping therethrough after they have been properly positioned.

As shown by Figure 3, the wings 6 are 50 provided with upper friction surfaces 9, which surfaces embody upwardly extended rubber projections adapted to engage the under surface of the strap 10, between the eyelets formed therein.

Ears 11 are formed on the body of the water bottle as illustrated by Figure 4, which ears are formed with elongated eyelets 12 for the reception of the securing straps.

The securing straps employed in connection with the bottle, are of the usual and well known construction, the same being provided with suitable buckles so that the straps may be secured around the limb or 65 body of a person to hold the water bottle in a fixed position with respect to the body.

I claim:—

1. In a device of the character described, a body portion, elongated laterally extending wings formed on the body portion, said laterally extending wings having eyelets formed adjacent to their ends, straps adapted to be passed through the eyelets, and said wings having friction surfaces contacting with the straps to prevent movement of the straps over the wings.

2. In a device of the character described, a body portion, elongated laterally extending wings formed on the body portion, said wings having spaced eyelets, a friction member positioned on each wing and arranged between the eyelets, straps adapted to be passed through the eyelets and adapted to overlie the friction members to hold the 85 body portion against movement with respect to the strap.

In testimony that I claim the foregoing as my own, I have hereto affixed my signature.

HENRIETTA PYLE.
